CLAIM

The ornamental design for a tripod, as shown and described.

DESCRIPTION

FIG. 1 is a first perspective view of a tripod showing my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the design features contained within circle 9 of FIG. 1; and,

FIG. 10 is an enlarged view of the design features contained within circle 10 of FIG. 7.

The broken lines in the drawing depict environmental structure and form no part of the claimed design.
